UNITED STATES PATENT OFFICE.

CHARLES FURNESS HATELY, OF CHICAGO, ILLINOIS, ASSIGNOR TO NATIONAL SURFACE GUARD COMPANY, OF CHICAGO, ILLINOIS, A CORPORATION OF ILLINOIS.

CATTLE-GUARD.

1,299,462.

Specification of Letters Patent.

Patented Apr. 8, 1919.

Application filed October 25, 1917. Serial No. 198,434.

To all whom it may concern:

Be it known that I, CHARLES FURNESS HATELY, a citizen of the United States, residing at Chicago, in the county of Cook and State of Illinois, have invented certain new and useful Improvements in Cattle-Guards, of which the following is a specification.

This invention relates to cattle guards, and has reference more particularly to cattle guards of the type that are made from sheet metal and are formed with integral teeth struck or stamped up from the body portion or portions of the guard. A cattle guard of the general class and structural type to which the present invention belongs is illustrated in Letters Patent to Bolinger, No. 1,156,856, dated October 12, 1915; and the object of the invention is to improve the utility and efficiency of sheet metal guards of the class shown in said patent, this object being attained principally by a novel construction of the tooth bars of the guard whereby a largely increased number of teeth for a given surface area is secured, and whereby also said teeth are more effectively and efficiently arranged or disposed over the surface of the guard. To this end, a cattle guard of my present invention comprises the various features and details of structure hereinafter described and more particularly defined in the appended claims.

In order that my invention may be readily understood and appreciated by those familiar with the art in which it belongs, I have illustrated in the accompanying drawings one practical and workable embodiment thereof; and referring thereto—

Figure 1 is a top plan view of a cattle guard of my invention shown as applied in use, a few only of the tooth bars being shown in full detail since they are all alike.

Fig. 2 is an enlarged fragmentary perspective view of one of the tooth bars.

Figs. 3 and 4 are sections on the corresponding lines of Fig. 1.

Referring to the drawing, 5 designates the ties and 6 the rails of a railway track to which the cattle guard is principally applied in service. As herein shown the complete guard is made in a plurality of sections disposed side by side, each section comprising a series of four parallel tooth bars rigidly connected in spaced relation. As the sections are all alike, a description of one will suffice for all.

A designates as an entirety each of the tooth bars, the ends 7 of which are flat and are riveted to transverse angle bars 8, these latter resting upon the ties 5 and being secured to the latter as by spikes 9. The 60 marginal portions of each bar are bent downwardly to form underlying ribs or flanges 10, and these latter fit into transverse kerfs 11 formed in underlying angle bars 12, of which one or more may be used depending upon the length of the guard, the angle bars 12 serving as connecting and spacing members and also preferably resting upon the ties 5. To lock the tooth bars A to the bars 12, the portions of the flanges 10 70 lying in the kerfs 11 are swaged laterally as indicated at 10' in Fig. 4 so as to form a lock. From the intermediate portion of the bar that lies between the flanges 10 there are struck up two rows of substantially vertical 75 main teeth 13 of inverted V-shape, these teeth lying substantially in the vertical planes of the ribs or flanges 10.

The guard as thus far described is substantially the guard disclosed in the Letters 80 Patent hereinabove referred to, with the exception that the intermediate skeleton web portion is of arch form instead of flat, this latter feature, however, forming no part of the present invention. My present improvements have to do with the structural form of the tooth bar itself, and consist of the features next to be described.

Out of each of the main teeth 13 is struck an auxiliary tooth 14 that extends laterally 90 of the main tooth on the outer side of the latter and preferably having an upward and outward inclination of approximately 45°. There is also preferably employed an additional row of teeth 15 lying parallel with 95 and substantially midway between the two rows of main teeth 13. These intermediate teeth 15 are very simply and easily produced by simply severing alternate limbs 16 of the zigzag skeleton structure that is 100 created by the punching out of the main teeth 13, these limbs being severed transversely and the longer portions of the severed limbs being bent upwardly as indicated in Fig. 2, thereby forming the upwardly 105 pointing teeth 15, while the shorter portions form substantially horizontal prongs or teeth 17.

One result of the foregoing structure is that the number of teeth in a given surface 110

area of the guard is doubled as compared with the structure of the Bolinger patent above referred to, and consequently the spacing of the teeth throughout the surface of the guard is reduced by approximately one-half. This renders the guard much more efficient not only for keeping horses and cattle off the railway track but also for preventing smaller hoofed animals such as hogs and sheep from crossing or trespassing on the railway track. Manifestly, the auxiliary teeth 14 serve to reduce the width of the open spaces between the bars, while the auxiliary teeth 15 similarly serve to reduce the space between the marginal teeth 13 of each bar. The result is a guard, the surface area of which is so thickly studded with projecting points that it is impossible for any farm animals to walk upon or over it.

20 While I have shown and described a simple and practical embodiment of the invention readily lending itself to economical manufacture by mere punching and swaging operations, it will be understood that the principle of the invention is capable of embodiment in tooth bars otherwise made and differing somewhat in specific detail. Hence, I do not limit the invention to the particular structure herein shown except to the extent indicated in specific claims.

I claim:

1. A cattle guard comprising a plurality of spaced bars, each provided with a longitudinal row of upstanding main teeth, and said main teeth carrying upwardly inclined auxiliary teeth struck out from the sides of said main teeth and merging their bases with the latter.
2. A cattle guard comprising a plurality of spaced bars, each provided on a longitudinal margin thereof with a row of substantially vertical main teeth, and said main teeth carrying flat auxiliary teeth struck out from the sides of said main teeth and merging at their bases with the latter and lying in a plane forming an acute angle with the portions of said main teeth above the bases of said auxiliary teeth.
3. A cattle guard comprising a plurality of spaced bars, each provided on a longitudinal

margin thereof with a row of substantially vertical inverted V-shaped main teeth, and said main teeth having punched therefrom upwardly and outwardly inclined inverted V-shaped auxiliary teeth struck out from the sides of said main teeth and merging at their bases with the latter and lying in a plane inclined at an angle of approximately forty-five degrees to the portions of said main teeth above the bases of said auxiliary teeth.

4. A cattle guard comprising a plurality of separated spaced bars, each formed with parallel vertical flanges and a connecting web, each of said vertical flanges having on its upper edge a row of vertical teeth struck upwardly from said web, and said web carrying an additional row of vertical teeth struck upwardly therefrom, and also a series of substantially horizontal prongs created by the striking up of said rows of teeth.

5. A cattle guard comprising a plurality of separated spaced bars, each formed with parallel vertical marginal flanges and an arched connecting web, each of said vertical flanges having on its upper edge a row of teeth struck upwardly from said web and lying in the vertical plane of the flange, and said web carrying an additional row of shorter teeth struck upwardly therefrom substantially midway between said marginal rows, and also a series of substantially horizontal prongs created by the striking up of said rows of teeth.

6. A cattle guard comprising a plurality of spaced bars, each provided on the longitudinal margins thereof with rows of upstanding teeth carrying outwardly and upwardly projecting auxiliary teeth, and with an additional longitudinal row of teeth between said marginal rows.

7. A cattle guard comprising a plurality of spaced bars, each provided on the longitudinal margins thereof with rows of upstanding teeth carrying outwardly and upwardly projecting auxiliary teeth, and further provided with an intermediate row of shorter teeth struck up from the intermediate portion of the bar.

C. FURNESS HATELY.
